CLAIM

The ornamental design for a shoe, as shown and described.

DESCRIPTION

FIG. 1 is a front bottom perspective view of a shoe showing my new design;

FIG. 2 is a bottom view thereof;

FIG. 3 is an opposite front bottom perspective view thereof;

FIG. 4 is rear bottom perspective view thereof; and,

FIG. 5 is an opposite rear bottom perspective view thereof.

The broken lines within the shaded area represent grooves which form no part of the claimed design. The broken lines depicting the remainder of the shoe show features that form no part of the claimed design.
